Primary Examiner—Martie Thompson[57] **CLAIM**

The ornamental design for a golf pencil holder, as shown and described.

DESCRIPTION

FIG. 1 is a perspective view of a golf pencil holder showing my new design;

FIG. 2 is a front elevation view thereof;

FIG. 3 is a rear elevation view thereof;

FIG. 4 is a top plan view thereof;

FIG. 5 is a right side elevation view thereof; and,
FIG. 6 is a front elevation view of a second embodiment of my new design of FIG. 1, all other views thereof corresponding to FIGS. 2 through 5.

The golf pencils depicted by means of broken lines in FIG. 1 have been shown for illustrative purposes only and form no part of the claimed design.

FIG. 1

FIG. 4

FIG. 2

FIG. 5

FIG. 3

FIG. 6
